(57) **CLAIM**

The ornamental design for an element of a water filter, as shown and described.

DESCRIPTION

FIG. 1 is a top perspective view of element of a water filter of the present invention;

FIG. 2 is top plan view thereof;

FIG. 3 is a bottom plan view thereof;

FIG. 4 is a front elevational view thereof;

FIG. 5 is a back elevational view thereof;

FIG. 6 is a right side elevational view thereof; and,

FIG. 7 is a left side elevational view thereof.

The broken line showing of a lower housing portion of a water filter in FIGS. 1-7 is environmental only and forms no part of the claimed design.
